UNITED STATES PATENT OFFICE.

ADAM M. GOODWIN, OF WILKINSBURG, PENNSYLVANIA.

REVERSING MECHANISM.

Original application filed August 9, 1920, Serial No. 402,272. Divided and this application filed October 25, 1921. Serial No. 510,257.

To all whom it may concern:

Be it known that I, ADAM M. GOODWIN, a citizen of the United States, and resident of Wilkinsburg, in the county of Allegheny and 5 State of Pennsylvania, have invented a new and useful Improvement in a Reversing Mechanism, of which the following is a specification.

This invention relates to a reversing mechanism, and is a division of copending application Serial No. 402,272, filed August 9, 1920.

For clothes washing machines and the like it is highly desirable that the drum of the 15 machine be rotated and that the direction of rotation be automatically reversed after a single revolution, or after a predetermined number of revolutions in the same direction.

It is also desirable that the reversing mechanism be compact in order to economize in the quantity of grease required for lubrication; that the parts be such as to minimize likelihood of breakage; and that the power transmitting means be smooth in operation 25 and simple to manufacture.

An object of the invention is, therefore, to provide reversing mechanism in which the reversing action is secured by means of a compact gear assembly without calling into 30 play lever or clutch during operation of the mechanism.

A specific object of the invention is to secure the reversal by the direct interaction of an assembly composed of spur gears; such 35 arrangement providing compactness in the elimination of lever arms, smoothness due to the superior meshing qualities of spur gears, and economy due to the elimination of the more expensive bevel gears.

40 In the accompanying drawings Figure 1 is a cross sectional view of the device; Figure 2 is a vertical section taken on the line 2-2 of Figure 1; Figure 3 is a detail elevation of a modified segmental pinion constituting an element of the device; and Figure 4 is a detail elevation of another segmental pinion arranged to produce a reversal in the direction of rotation of the power shaft after each single revolution thereof.

50 The reversing mechanism of the present invention is preferably contained in a suitable casing 1, which may be filled with grease to lubricate the moving parts of the mechanism. Power is transmitted to the mechanism by means of a shaft 2, mounted

in a bearing 3 in the casing and carrying a sheave 4 for connection with a suitable source of motive power. Shaft 2 also carries a pinion 5, which meshes with a gear 6 keyed or splined on a cross shaft 7. 60

A driven shaft 8 is mounted in the casing 1 and has thereon a gear 9. Means are provided whereby the rotation of gear 6 in a uniform direction produced a reversal in the direction of rotation of the gear 9 and driven shaft 8 after a predetermined number of revolutions in either direction.

These means comprise a bracket 10 which is rotatably mounted on the cross shaft 7, and which is of a general oblate U-shape in 70 longitudinal section. The bracket 10 is provided with a relatively stiff helical spring 11 secured to the bracket and to the case 1, this spring being for the purpose of maintaining the bracket in one or the other of the 75 positions which it assumes in operation of the mechanism.

Rotatably mounted in bracket 10 are the pinions 12 and 13 meshing with the gear 14. Also rotatably mounted in the bracket 80 10 is a pinion 15 meshing with pinion 12. In different positions of the bracket, pinions 13 and 15 are respectively brought into mesh with the gear for revolving the driven shaft. 85

The means for alternately throwing pinions 13 and 15 into mesh with gear 9 comprise a pin 16 on the back of bracket 10, a pin 17 on a face of gear 9, and a segmental pinion 18 having thereon teeth arranged to project into the path of movement of pin 17 and to contact with pin 16. The segmental pinion 18 is likewise rotatably mounted on bracket 10 and is provided with a number of teeth corresponding 90 to the number of revolutions which it is desired to impart to driven shaft 8 between reversals of its direction of rotation. 95

Assuming that gear 14 is rotating uniformly in a counter-clockwise direction, the pinion 12 will be rotated in a clockwise direction, and the pinion 15, meshing with gear 9 will be rotated in a counter-clockwise direction. The pinion 13 will be rotating 100 idly in a clockwise direction. This action continues until the gear 9 has made a sufficient number of revolutions to cause the end tooth 20 to come into contact with pin 16 on bracket 10. The tooth 20 contacting 105 110

pin with 16, due to the rotation of gear 9, causes a rotational movement of the bracket 10, forcing spring 11 past its dead center into the position indicated in dotted lines 5 in Figure 2 of the drawings. This rotational movement throws pinion 15 out of mesh with gear 9 and throws pinion 13 into mesh therewith, so that gear 9 is rotated in a counter-clockwise instead of a clockwise 10 direction.

With the parts in this position, the segmental pinion 18 is rotated back tooth by tooth until the other end tooth 19 comes into contact with pin 16, causing another reversal 15 in the direction of rotation of gear 9 and shaft 8.

Obviously by varying the number of teeth on the segmental pinion 18, the number of revolutions between reversals may be varied 20 up to the limit set by the available space on the toothed segment of the pinion.

Thus the segmental pinion shown in Figure 3 of the drawings produces a reversal in the direction of rotation of the driven 25 shaft for every three revolutions thereof, and the segmental pinion shown in Figure 4 of the drawings produces a reversal in the direction of rotation of the power shaft for each single revolution thereof.

30 The device of the present invention is particularly adapted for use in producing the desirable reversals in the direction of rotation of the drum of a washing machine, because of its compact and economical structure. It also presents advantages for this 35 and other uses in the utilization of spur gears only, and in the fact that such gears operate directly in causing reversals in the direction of rotation without the use of 40 clutch or similar mechanism.

This obviates necessity for the use of worms, cams, levers, or the like. It is to be noted that the mechanism is wholly automatic in its operation.

45 As the device is susceptible of a number of modifications without departing from the spirit of the invention, only those limitations contained in the appended claims are 50 to be imposed upon the scope of the invention.

What I claim is:

1. Reversing mechanism comprising a 55 movable bracket, a driven shaft, a gear thereon, driven pinions in said bracket and arranged to mesh one at a time with the gear on said driven shaft for driving the same in opposite directions of rotation, a segmental pinion, and a projection on the gear of said driven shaft arranged to actuate said segmental pinion for causing it to operate upon the bracket to alternate the meshing of said pinions with the gear on said driven shaft.

60 2. Reversing mechanism comprising a 65 movable bracket, a driven shaft, a gear thereon, driven pinions in said bracket arranged

to mesh one at a time with the gear on said driven shaft for driving the same in opposite directions of rotation, a segmental pinion, a projection on the gear of said driven shaft arranged to engage a tooth of said segmental pinion upon each revolution of the power shaft, and a projection on said bracket arranged to be engaged by said segmental pinion to alternate the meshing of said pinions with the gear on the driven shaft. 75

3. Reversing mechanism comprising a driving shaft, a gear thereon, a movable bracket, pinions on said bracket actuated in mutually opposite directions of rotation by said gear, a driven shaft, a gear on said driven shaft, and a member rotatably mounted on said bracket and arranged to be actuated directly by said driven shaft to shift the bracket after a predetermined number of revolutions of the driven shaft and alternate the meshing of said pinions with the gear on the driven shaft. 85

4. Reversing mechanism comprising a driving shaft, a gear thereon, a movable bracket, pinions on said bracket actuated in 90 mutually opposite directions of rotation by said gear, a driven shaft, a gear on said driven shaft, and a segmental pinion arranged to be rotated step by step by said driven shaft to shift the bracket after a predetermined number of revolutions of the driven shaft and alternate the meshing of said pinions with the gear on the driven shaft. 95

5. Reversing mechanism comprising a 100 movable bracket, a driven shaft, a gear on said driven shaft, pinions in said bracket arranged to mesh one at a time with the gear on said driven shaft for driving the same in opposite directions of rotation, and a member rotatably mounted on said bracket and arranged to be actuated directly by said driven shaft to shift the bracket after a predetermined number of revolutions of the driven shaft and alternate the meshing of 105 said pinions with the gear on the driven shaft.

6. Reversing mechanism comprising a 110 movable bracket, a driven shaft, a gear on said driven shaft, pinions in said bracket arranged to mesh one at a time with the gear on said driven shaft for driving the same in opposite directions of rotation, and a segmental pinion arranged to be actuated directly by said driven shaft to shift the bracket after a predetermined number of revolutions of the driven shaft and alternate the meshing of said pinions with the gear on the driven shaft. 115

7. Reversing mechanism comprising a 125 movable bracket, a driven shaft, a pair of rotatably mounted members on said bracket arranged to alternately impart movement of rotation to the driven shaft, means for positively rotating said members in opposite di- 130

- rections, and a segmental pinion arranged to be actuated directly by said driven shaft after a predetermined number of revolutions of the driven shaft to shift the bracket and positively rotated members thereon for reversing the direction of rotation of the driven shaft.
8. Reversing mechanism comprising a movable bracket, a driven shaft, an engaging member thereon, driven members rotatably mounted in said bracket and arranged to engage one at a time with the member on the driven shaft for driving said shaft in opposite directions of rotation, a segmental pinion, and a projection on the engaging member of the driven shaft arranged to actuate said segmental pinion for causing it to act upon the bracket to alternate the engagement of the rotatably mounted members on the bracket with the engaging member on the driven shaft.

9. Reversing mechanism comprising a driving shaft, a driving member thereon, a movable bracket, rotatably mounted members on said bracket actuated in mutually opposite directions of rotation by said driving member, a driven shaft, an engaging member on said driven shaft, and a member rotatably mounted on said bracket and arranged to be actuated directly by said driven shaft to shift the bracket after a predetermined number of revolutions of the driven shaft to alternate the engagement of the rotatably mounted members on the bracket with the engaging member on the driven shaft.

In witness whereof, I hereunto set my hand.

ADAM M. GOODWIN.
